US00D973082S

(12) **United States Design Patent** (10) Patent No.: **US D973,082 S**
(45) Date of Patent: **** Dec. 20, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Arian Behzadi**, San Francisco, CA (US); **Lee S. Broughton**, Santa Cruz, CA (US); **Christopher P. Foss**, San Francisco, CA (US); **Deena Ahmed Khattab**, San Francisco, CA (US)

(73) Assignee: **Apple Inc.**, Cupertino, CA (US)

(**) Term: **15 Years**

(21) Appl. No.: **29/779,571**

(22) Filed: **Apr. 20, 2021**

(51) LOC (13) Cl. **14-04**

(52) U.S. Cl.

USPC **D14/486**

(58) **Field of Classification Search**

USPC **D14/485-495**

CPC G06F 3/048; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/04855; G06F 3/0486; G06F 3/04886; G06Q 30/00; G06Q 30/02; G06Q 30/0237; G06Q 30/0238; G06Q 30/0239; H03J 1/00; H03J 1/0008; H03J 1/0016; H03J 1/0025; H04N 5/00; H04N 5/08; H04N 5/14; H04N 5/222; H04N 5/225; H04N 5/232; H04N 5/23222; H04N 5/23293; H04N 5/232933; H04N 5/232935; H04N 5/445; H04N 5/44504; H04N 5/45; H04N 21/00; H04N 21/234; H04N 21/431; H04N 21/4312; H04N 21/4314; H04N 21/4316; H04N 21/4532; H04N 21/4622; H04N 21/47; H04N 21/478; H04N 21/482; H04N 21/4884; H04N 21/4888; H04N 21/4856; H04N 21/485; H04N 21/6547

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
